GRINDING MACHINE

Clement Booth, Cincinnati, Ohio, assignor to
 Cincinnati Grinders Incorporated, Cincinnati,
 Ohio, a corporation of Ohio

Application July 3, 1931, Serial No. 548,610

26 Claims. (Cl. 51—103)

This invention relates to improvements in grinding machines and especially to improvements in what are commercially known as centerless grinders.

5 An object of the invention is the provision of an improved substantially automatic grinding machine for grinding formed work pieces, such as grooved inner bearing races.

Another object of the invention is the provision 10 of an improved automatic grinding machine including automatic loading and ejecting mechanism operated and controlled by hydraulic pressure.

A further object of the invention is the provision 15 of improved means for loading formed work pieces, such as the bearing races above noted, into and removing same from the throat of a centerless grinder.

A still further object of the invention is the 20 provision of improved individual means for inserting the work within the grinding throat and improved individual means for removing same therefrom, each operating in a cyclic sequence, whereby lost time in actual production of the 25 machine is greatly reduced.

Other objects and advantages of the present 30 invention should be readily apparent by reference to the following specification considered in conjunction with the accompanying drawings and it is to be understood that any modifications may be made in the exact structural details 35 there shown and described, within the scope of the appended claims, without departing from or exceeding the spirit of the invention.

35 In the drawings:

Figure 1 is a front elevation of a centerless grinding machine embodying the improvements of this invention.

40 Figure 2 is a view as seen from line 2—2 of Figure 1.

Figure 3 is a fragmentary illustration of the 45 parts above the broken portion of Figure 2.

Figure 4 is a view transversely of that shown 50 in Figure 2 and illustrating the relative position of the parts forming the grinding throat.

Figure 5 is a view as seen substantially from 55 line 5—5 of Figure 2, and illustrating the insertion and positioning of the work within the grinding throat.

Figure 6 is a detail view of the pressure sleeve showing certain details of the invention.

Figure 7 is a sectional view taken substantially 60 on line 7—7 of Figure 1.

55 Figure 8 is a sectional view taken on line 8—8

of Figure 7, certain parts being broken away to more clearly illustrate the structure.

Figure 9 is a sectional view taken on line 9—9 of Figure 7.

Figure 10 is a diagrammatic view illustrating 5 the hydraulic circuit employed in the performance of the invention and showing the several positions of the valve for automatically effecting the different functions of the machine.

Figure 11 is a sectional view illustrating a 10 modification of certain parts of the invention.

Throughout the several views of the drawings similar reference characters are employed to denote the same or similar parts.

A device of this invention may comprise a bed 15 10 having rising therefrom a pedestal bearing 11 supporting a spindle 12 on which is secured a pair of grinding wheels 13. The grinding wheels 13 are opposed to a pair of regulating wheels 14, likewise mounted on a spindle 15 carried by 20 housing 16 secured to a slide 17. The slide 17 is mounted on a second or lower slide 18 supported on ways 19 formed on the bed 10. The slides 17 and 18 are adapted to be actuated relative to one another and relative to the bed 10 for which 25 purpose clamps 20 and 21 are provided, the former for securing the upper slide 17 to the lower slide 18, whereby the slides are moved as a unit, and the latter for securing the lower slide 18 to the bed 10 whereby slide 17 is moved 30 relative to slide 18.

The operative faces of the wheels 13 and 14 are spaced from one another to provide a grinding throat in which the work 22 is positioned for operation thereon. The parts are so related as 35 to simultaneously grind the bearing grooves 23 of a pair of individual races or work pieces 22, or for grinding simultaneously the grooves of a double antifriction bearing which is frequently 40 employed in various industries. In order to properly support the work piece or pieces in simultaneous engagement with the grinding and regulating wheels, the lower slide 18 is provided on its inner end with a supporting block 24 45 supporting a work rest blade 25 having a pair of contact or support portions 26 positioned while in operation within the grooves being ground, as seen in Figures 4 and 5. The said supporting portions 26 are positioned beyond the center of the throat and nearer the grinding wheel, being 50 further provided with an inclined operative portion as at 27 inclining toward the regulating wheels and with the surface of said wheels forming a work receiving trough.

The work is initially positioned within a maga- 55

zine or feed chute 28 extending along the forward portion of the machine and inclining toward the entrant side of the grinding throat so that the work is brought to the said grinding throat by gravity. The magazine or trough 28 terminates in a platform 29 and the magazine has extending over the lower end thereof a guide strip 30 spaced sufficiently from the top of the work piece to permit its free movement under the influence of gravity, but preventing any side-wise tilting of the work for a reason which will appear later.

The platform 29 is secured to a bracket or stand 31 secured as by bolts or other fastening means 32 to block 24 at the forward end of the lower slide 18. The bracket 31 is formed with a cylinder 33 into which is pressed a liner or bushing 33A encircling a sleeve 34 adapted to be slidably actuated therethrough. The sleeve 34 in turn encloses a plunger 35 having a guideway 36 formed therein which receives the end 37 of a screw 38 whereby relative oscillatory movement between the plunger 35 and sleeve 34 is prohibited. The plunger and sleeve, when in a retracted position, are clear of the magazine or chute 28 so that the lowermost work pieces may position themselves on the platform 29. Further, the diameter of the plunger 35 is such as to freely enter the bore within the work pieces 22 in order to pick up the work pieces from the platform 29.

The sleeve 34 has extending from it a hollow piston rod 39 to which is secured or integrally formed therewith a piston 40 enclosed within an hydraulic cylinder 41. The cylinder 41 is closed at its forward end by a cylinder head 42 which in turn forms a flange 43 through which cap screws, or the like, extend for fastening the cylinder 41 to the end of the cylinder 33. The other end of the cylinder 41 is closed by a cylinder head 44 and has secured thereto one end of a conduit 45. The piston 40 is provided with a hollow interior which is closed at one end by a cap 46 into which one terminus of a conduit 47 is secured. Enclosed within the piston 40 is a second piston 48 on the end of a piston rod 49 extending from the plunger 35 through the hollow piston rod 39. A port 50 is formed in the end of the piston 40 opposite to that to which the cap 46 is secured and the hydraulic cylinder 41 is provided with a conduit 51 at the end adjacent the cylinder head 42.

The operation of the parts just described is as follows: A pair of bearing races 22 are positioned on the platform 29 whereupon the piston 48 is actuated relative to the piston 40 for inserting the end of plunger 35 within the bore in the races. Hydraulic pressure is then introduced through the conduit 45 for effecting a movement of pistons 40 and 48 to carry the work pieces from the position outside the grinding throat to a point within the grinding throat.

The sleeve 34 has formed in its outer surface a cam slot 52 in which is positioned a pin 53 extending from the inner wall of the cylinder 33. The slot 52 is provided with a pair of parallel portions 54 and 55, being connected at opposite ends by inclined portions 56 and 57. The slot extends through 90 degrees of the surface of the sleeve 34, as shown most clearly in Figure 6. The plunger 35, as seen in Figure 5, is provided with a cutaway portion terminating in the line 58 as shown therein.

When the sleeve and plunger are in a retracted position, the cut-away portion is positioned lat-

erally of the axial center of the plunger so that the work contacts with the outer periphery of the plunger, as seen in full lines in Figure 5. At this time the pin 53 is in the lower parallel slot 55 as seen in Figure 6. As the parts are advanced, as above described, the pin advances to the inclined portion 57, whereupon continued forward motion of the sleeve causes, through interengagement of the pin 53 and slot 57, a combined forward axial movement and a rotation of the sleeve and plunger through an arc of 90 degrees, thereby turning the plunger 35 in a counter-clockwise direction and placing the cut-away portion 58 uppermost so that when the work pieces are within the grinding throat they drop onto the supporting portions 26 of the blade which, as above described, enters the grooves formed therein. From this it will be seen that during the actual grinding operations the work is supported only on the work rest blades as is customary centerless grinding practice. The position of the parts during the grinding operation is illustrated in dotted lines in Figure 5.

At the other end of the grinding throat the block 24 at the forward end of the slide 18 has secured thereto a bracket 59 split as at 60 and receiving within a bore a stop block 61 against which the adjacent face of the work pieces is held by hydraulic pressure continuing against the piston 40 causing the end of the sleeve 34 to hold the work for rotation in a definite vertical plane. This is necessary to insure the rotation of the work in a plane parallel to the finished faces thereof to enable the grooves to be properly formed therein.

The work is fed into the grinding wheels automatically by the mechanism particularly illustrated in Figures 1, 7 and 8. This mechanism includes a housing 62 having extending therefrom a bracket 63 whereby it is secured to an extended flange portion 64 of the bed 10. The housing 62 has journaled therein the reduced end 65 of an adjusting screw 66 in threaded engagement with a nut 67 carried by the upper slide 17. The screw 66 has secured to its outer end a pilot or hand wheel 68 whereby it may be rotated for initially adjusting the parts and setting the grinding throat. The housing 62 is formed interiorly thereof with a bearing 69 in which is slidably mounted a slide block 70 encircling the reduced portion 65 of the screw 66 and flanked on opposite ends by collars 71 and 72. Toggle arms 73 extend from opposite sides of the block 70 and are pivotally secured at their outer ends to lugs 74 of crank 75 pivoted as at 76 to the walls of the housing 62. The lower end of the arm 71 of the crank 75 carries an adjustable roller 78 received in a cam groove 79 of cam 80. This cam 80 is secured for movement with a cam shaft 81 journaled in bearing 82 of the housing 62 which is driven by a worm wheel 83 secured thereto. The worm wheel in turn is driven through a worm 84 on worm shaft 85 geared at 86 to a prime mover secured to the housing 62.

The cam groove 79 is provided with a portion 88 from which an outwardly abruptly flaring portion 89 continues for rapidly shifting the roller 78 from the center of the shaft 81 to thereby rapidly advance the regulating wheel unit to the grinding position. The groove then continues as at 90 at a uniform rate for effecting the relative feed between the work pieces and the grinding wheels and said portion terminates in a relatively concentric portion 91 which effects a dwell in the movement of the work and grind-

ing wheel to permit the grinding wheel to spark out and provide the desired finish on the work. The portions 88 and 91 are again joined by an abrupt decline 92 for rapidly retracting the regulating wheel unit from a grinding position to a position to permit the withdrawal of the finished work pieces from the grinding throat and the insertion therein of unfinished work pieces.

Secured on the cam shaft 81 for movement therewith is a second cam 93 having a cam slot 94 formed therein and receiving a roller 95 secured to an arm 96 intermediate its ends. One end of the arm 96 is pivoted at 97 to the housing 62 and the other end is provided with an elongated slot 98 receiving a pin 99 extending from a valve stem 100. The valve stem 100 is integral with a valve 101 axially shiftable through a valve bushing 102 pressed into housing or casing 103. The valve operating cam 93 by rotation 20 with the cam 80 effects a shifting of the valve in timed sequence with the movement of the regulating wheel toward and from the grinding wheel.

After the work has been reduced to size and 25 to eject the said work from the grinding throat the following mechanism is resorted to. Secured to the block 24 at the rear end thereof, as by bolts 104, is a cylinder 105 containing piston 106 adapted to be reciprocated through the said cylinder. Extending from the piston 106 is a piston rod 107 having secured to its upper or free end a beam 108 from which depend ejector arms 109 and 110. The arms 110 have yieldably pivotally secured at their free ends fingers 111 and 112. 30 The said fingers have respectively extending therefrom tangs or lugs 113 and 114 adapted to engage pins 115 and 116 to limit their movement under yielding pressure in a given direction. As seen in Figure 2, the said fingers extend toward 40 one another and lie within the space defined by adjacent sides of the arms 109 and 110.

Secured to the regulating wheel housing 13 is a bracket 117 from which bracket 118 extends having rising therefrom posts 119 and 120. The 45 posts 119 and 120 are each provided with a holding finger 122 and 123, similar to the carrying fingers 111 and 112, the said fingers being normally yieldably rotated about their pivotal mountings to maintain their lugs 124 in engagement 50 with studs 125 so that the operative portion of the fingers lie within the space between opposed faces of the posts 119 and 120. Extending from the bracket is a chute 126 adapted to receive the work pieces when discharged from the grinding 55 throat, the said work pieces being deflected into the chute 126 by a deflector plate 127 secured to and carried by the posts 119 and 120.

The operation of the discharging mechanism is as follows. Hydraulic pressure is introduced, 60 by means to be described later, into the upper end of the cylinder 105 causing a descent of the piston 106, as seen in Figure 2, which carries with it the arms 109 and 110. As the arms descend the fingers 111 and 112 engage the outer opposite peripheries of the work pieces causing same to be deflected or actuated in an outward direction until the bore of the work piece is reached whereupon the yielding means inserts the operative portion of the fingers within the interior of 70 the work. Hydraulic pressure is now introduced into the bottom of the cylinder 105 for effecting a raising of the piston 106 in said cylinder whereupon the said work pieces are carried out of the grinding throat by the said carrying fingers 111 and 112. The work pieces continue in an upward

direction between the posts 119 and 120 where the work pieces effect a similar actuation of the holding fingers 122 and 123. The next downward movement of the piston 106 and parts carried thereby causes the carrying fingers 111 and 112 to leave the interior of the work leaving it to hang on the holding fingers 122 and 123, as seen in Figures 2 and 4. The next upward movement of the piston 106 with the finished work pieces causes same to push the work pieces on the holding fingers 122 and 123 upwardly into engagement with the deflector 127 whereby they are shunted into the work receiving trough 126 to a suitable receptacle, not shown, placed in proper position to receive same. 15

The hydraulic circuit for operating the loading and ejecting mechanisms is diagrammatically illustrated in Figure 10, as are the several operative positions of the valve. The valve body 101 is provided with cannelures 128, 129, 130 and 131 20 for effecting the several operative positions. The several positions are indicated in Figure 10 at 132, 133, 134, 135 and 136. The valve is adjusted to this position by the cam groove 94 which has a concentric portion 137 of a considerable part 25 of the cycle which represents the time of the grinding and dwell at which time there is no relative movement of the valve and hydraulically actuated parts. The portion 137 of the cam groove 94 terminates in the portion 138 which effects the shifting of the valve 101 to the second position 133. Portions 139, 140 and 141 likewise effect the remaining positions of the valve for 30 properly cyclically operating the loading and ejecting mechanisms. 35

A hydraulic medium contained within a tank or sump 142 is circulated through the system by a pump 143 being discharged from the pump into pressure line 144 from which branch lines 145, 146 and 147 extend. As shown in Figure 10, 40 with the valve in the position "A" the hydraulic pressure from branch conduits 145 and 147 is blocked by the valve 101, while the pressure from branch 146 passes through the cannelure 130 the conduit 148 to the in-take conduit 51, port 50 for 45 retracting the inner piston 48 and withdrawing the plunger 35 from the interior of the work. The hydraulic medium in the piston cylinder 41 ahead of piston 48 is exhausted through pipe 47 to conduit 149 to the valve 100 which directs 50 it to the branch exhaust line 150 connecting with the main exhaust 151 to return the medium to the tank or sump 142.

When the grinding has been about completed the portion 141 of the groove 94 shifts the valve 55 to the position shown at "B", at which time the hydraulic pressure in branch lines 146 and 147 is blocked while the pressure in branch line 145 passes through cannelure 128 into the conduit 152 which terminates at the upper end of the 60 cylinder 105 for effecting the descent of the piston 106 therein. The exhaust from the cylinder 105 is directed through conduit 153 to the valve where the cannelure 129 connects the said conduit 153 with exhaust branch conduit 154 in turn connected with the main exhaust conduit 151 for 65 returning the hydraulic medium to the sump or tank 142.

Further continued rotation of the cam 93 effects a shifting of the valve 101 to the position "C" 70 through the portion 140 of the cam groove 94. In this position the hydraulic medium in branch pressure line 147 is blocked while the pressures in branches 145 and 146 are connected respectively through the cannelure 128 with the conduit 153 75

for raising the piston 106 in the cylinder 105 and with the conduit 148 for, at this time, retracting both the inner piston 48 and the outer piston cylinder 40 to the position shown in Figure 2. The exhaust ahead of the piston 106 in the cylinder 105 is by way of conduit 152 to the valve 101 where it is connected with branch exhaust conduit 155 in turn connected with the main exhaust conduit 151. The exhaust behind the piston cylinder 40 is directed through pipe 45 to the conduit 156 which terminates at the valve 101 and is connected thereby with the branch exhaust conduit 150.

The cam portion 139 next adjusts the valve to the position indicated as 135 which is the position indicated at "D" in the Figure 1. The pressure at this time in branch pressure line 146 is blocked, while the pressures in branch lines 147 and 145 are respectively connected through cannelure 131 with conduit 149 and pipe 150 for actuating the piston 48 relative to the piston cylinder 40 and the conduit 153 for maintaining the piston 106 in a raised position. This shifting of the piston 48 to the left, as seen in Figure 2, causes plunger 35 to pick up the next pair of work pieces to be placed within the grinding throat.

The portion 138 immediately shifts the valve to the position indicated at 134 illustrated at "E" in the figure, whereupon the pressure from branch lines 145 and 147 is blocked while the pressure from branch line 146 is directed by the cannelure 130 to the conduit 156 and pipe 45 for actuating the piston cylinder 41 together with the contained piston 48 to the left, as seen in Figure 2, thereby placing the work pieces within the grinding throat.

The next adjustment of the cam 93 again brings into play the portion 137 whereupon a repetition 40 of the cycle above described follows.

It should be noted that the above operation passes continuously through the several parts of the cycle so that the loading and ejecting mechanisms are operating substantially simultaneously thereby reducing the idle time of the machine 45 to an absolute minimum.

It will be noted that the work pieces are held between the sleeve 34 and the block 61 during the descent of the arms 109 and 110. In order 50 to accommodate the said arms so that the carrying fingers 111 and 112 are positioned within the bore before the pressure is released therefrom, the opposed faces of the said sleeve, block, and plunger 35 are respectively provided with 55 a groove 157, 158 and 159 of a width to accommodate both the arm and its carrying finger.

In Figure 11 a slight modification is illustrated in permitting a yielding pressure to be exerted against the work instead of the normal hydraulic pressure utilized for actuating the parts. As 60 there shown, the forward end of the sleeve 34 is reduced as at 160 surrounding which is a cup 161 being held from inadvertent disassociation by a nut 162 secured on the end of the sleeve extension 160. Interposed between the cup and sleeve is a coiled spring 163 abutting on opposite ends with the shoulder 164 of the sleeve and the base 165 of the cup. A key 166 may be provided to maintain definite relation between the 65 sleeve and cup so that the slots for the carrying arms and fingers will not be misaligned during operation.

What is claimed is:

1. In a grinding machine the combination of a 75 work support, a grinding wheel adjacent the sup-

port, hydraulically actuated means for positioning a work piece on the support, and additional hydraulically actuated means for removing the work piece from the support at the conclusion of the grinding operation thereon.

2. In a grinding machine the combination of a work support, a grinding wheel adjacent the support, means for loading a work piece on the support, means for ejecting the work piece from the support at the conclusion of the grinding 15 operation thereon, means for substantially simultaneously actuating the work loading and ejecting means, and means for synchronizing the actuation of said loading and ejecting means.

3. In a grinding machine the combination of a work support, a grinding wheel adjacent the support, means for loading a work piece on the support, means for ejecting the work piece from the support at the conclusion of the grinding 15 operation thereon, means for substantially simultaneously actuating the work loading and ejecting means, means for synchronizing the actuation of said loading and ejecting means, and a regulating member adjacent the work support and opposed to the grinding wheel for controlling the 20 rotation of the work during the grinding operation thereon.

4. In a grinding machine the combination of a work support, a grinding wheel adjacent the support, means for loading a work piece on the support, means for ejecting the work piece from the support at the conclusion of the grinding operation thereon, means for substantially simultaneously actuating the work loading and ejecting means, means for synchronizing the actuation 35 of said loading and ejecting means, a regulating member adjacent the work support and opposed to the grinding wheel for controlling the rotation of the work during the grinding operation thereon, and means for effecting a relative feed between the work and grinding wheel.

5. In a centerless grinder for grinding the exterior surfaces of hollow work pieces the combination of a pair of opposed grinding and regulating wheels forming a grinding throat therebetween, means within the throat for supporting a work piece in simultaneous engagement with the grinding and regulating wheels, means adapted to enter the bore in the work for loading same on the support from a point outside the 50 grinding throat, and additional means received within the bore for ejecting the work from the grinding throat.

6. In a grinding machine the combination of a grinding wheel, a work support adjacent the grinding wheel, means for shifting the work laterally of the grinding wheel to place same on the work support, and means for shifting the work in an angularly related direction to the loading movement for ejecting the work from the support.

7. In a grinding machine the combination of a grinding wheel, a work support adjacent the grinding wheel, means for shifting the work laterally of the grinding wheel to place same on the work support, means for shifting the work in an angularly related direction to the loading movement for ejecting the work from the support, and means synchronizing the actuation of the loading and ejecting means whereby the unfinished work may be mounted on the support substantially simultaneously with the removal of the finished work therefrom.

8. In a grinding machine the combination of a grinding wheel, a work support adjacent the 75

- grinding wheel, means for shifting the work laterally of the grinding wheel to place same on the work support, means for shifting the work in an angularly related direction to the loading movement for ejecting the work from the support, means synchronizing the actuation of the loading and ejecting means whereby the unfinished work may be mounted on the support substantially simultaneously with the removal of the finished work therefrom, means for effecting a relative feed between the work and grinding wheel while on the support, and means synchronizing the actuation of the feeding means and the loading and ejecting means.
- 15 9. In a centerless grinder the combination of a pair of opposed grinding and regulating wheels forming a grinding throat therebetween, a work support subtending the grinding throat, the grinding throat having an entrant side, a magazine for conveying work pieces to the entrant side of the grinding throat, means for moving work pieces from the entrant side of the throat onto the work rest blade within the throat, a discharge chute, and additional means for conveying work pieces from the work support to the discharge chute and automatically discharging the work from the machine.
- 20 10. In a centerless grinder the combination of a pair of opposed grinding and regulating wheels forming a grinding throat therebetween, a work support subtending the grinding throat, the grinding throat having an entrant side, a magazine for conveying work pieces to the entrant side of the grinding throat, means for moving work pieces from the entrant side of the throat onto the work rest blade within the throat, a discharge chute, and additional means for conveying work pieces from the work support to the discharge chute and automatically discharging the work from the machine, means for effecting an enlargement and contraction of the grinding throat to permit the insertion and removal of work therefrom, and means synchronizing the operation of said throat actuating means with the operation of the loading and ejecting means.
- 25 11. A loading mechanism for placing work pieces on a work support the combination of a magazine, a work pick up and shifting mechanism at the base of the magazine comprising a bracket, a sleeve therein, a plunger within the sleeve adapted to enter a bore in the work, and means for independently and successively actuating the plunger and sleeve for first picking up the work and subsequently moving same from the magazine to the work support.
- 30 12. A loading mechanism for placing work pieces on a work support the combination of a magazine, a work pick up and shifting mechanism at the base of the magazine comprising a bracket, a sleeve therein, a plunger within the sleeve adapted to enter a bore in the work, means for independently and successively actuating the plunger and sleeve for first picking up the work and subsequently moving same from the magazine to the work support, said means including an individual piston for the sleeve and plunger, a cylinder for each piston, and a hydraulic circuit, for actuating the pistons relative to their cylinders.
- 35 13. A loading mechanism for hollow cylindrical work pieces for placing same within the throat of a centerless grinder comprising a bracket in alignment with the grinding throat, a work rest blade within the grinding throat adapted to enter an under-cut formed portion of the work,
- a sleeve within the bracket and operable relative thereto, a plunger adapted to enter the bore in the work, means for actuating the plunger and sleeve successively for first picking up the work from the magazine and subsequently moving same into the grinding throat, and means for automatically effecting a drop of the work from its line of movement to position the work rest blade within the under-cut formed portion of the work.
- 40 14. A loading mechanism for hollow cylindrical work pieces for placing same within the throat of a centerless grinder comprising a bracket in alignment with the grinding throat, a work rest blade within the grinding throat adapted to enter an under-cut formed portion of the work, a sleeve within the bracket and operable relative thereto, a plunger adapted to enter the bore in the work, means for actuating the plunger and sleeve successively for first picking up the work from the magazine and subsequently moving same into the grinding throat, means for automatically effecting a drop of the work from its line of movement to position the work rest blade within the under-cut formed portion of the work, said means comprising a cam track formed in the sleeve member, and a follower carried by the bracket cooperating with the cam track.
- 45 15. In a centerless grinder for grinding formed portions of revolution in work pieces of greater dimensions than the portion to be ground the combination of opposed grinding and regulating wheels forming a grinding throat between them, the grinding throat having one end open to permit introduction of work therein, a work rest blade within the throat for engaging the work at the portion being operated upon, a block at the other end of the grinding throat and opposed to the entrant portion thereof, means transferring the work from a point outside of the grinding throat to the work rest blade, and means holding the work against the throat closing block to insure rotation of the work concentric with its axis.
- 50 16. In a centerless grinder the combination of a bed, a pair of opposed grinding and regulating wheels forming a grinding throat therebetween, means for shifting one of the wheels toward and from the other including a cam, a work rest blade within the grinding throat, means for loading a work piece on the blade, means for ejecting the work piece from the blade, a hydraulic circuit for actuating the said loading and ejecting means, a valve for controlling the hydraulic circuit to effect synchronized timed actuation of the loading and ejecting means, and a cam member for actuating the valve.
- 55 17. In a centerless grinder the combination of a bed, a pair of opposed grinding and regulating wheels forming a grinding throat therebetween, means for shifting one of the wheels toward and from the other including a cam, a work rest blade within the grinding throat, means for loading a work piece on the blade, means for ejecting the work piece from the blade, a hydraulic circuit for actuating the said loading and ejecting means, a valve for controlling the hydraulic circuit to effect synchronized timed actuation of the loading and ejecting means, a cam member for actuating the valve, and means for rotating the cams in unison for synchronizing the wheel movements with the movements of the loading and ejecting means.
- 60 18. A hydraulic loading and ejecting mechanism for use with a centerless grinder for posi-

- tioning hollow work pieces within the throat of the centerless grinder and for ejecting same therefrom comprising a plunger adapted to enter the bore of the work piece, a piston for shifting the work piece from a point exterior of the throat to a point within the throat, means adapted to enter the bore in the work piece for ejecting the work from the throat, a second piston for operating said ejecting means, a hydraulic circuit for actuating the plunger and the two pistons, a valve controlling the circuit, and means for shifting the valve to a plurality of positions for subsequently operating the plunger and two pistons.
19. In a machine tool organization the combination of a tool, a work support adjacent the tool and adapted to hold the work piece in operative relation to the tool, hydraulic means for placing the work on the support and removing it therefrom including a valve, and means for automatically varying the position of the valve for automatically picking up a work piece, placing same on the work support, releasing it, and ejecting the work from the support.
20. In a machine tool organization the combination of a tool, a work support for supporting a work piece adjacent the tool, hydraulically actuated means for picking up a work piece and placing same on the work support, hydraulically actuated means for removing the work from the support at the conclusion of the tooling operation, a single source of hydraulic pressure for operating said hydraulically controlled means, and a single valve distributing the pressure to the several hydraulic means.
21. In a machine tool organization the combination of a tool, a work support for supporting a work piece adjacent the tool, hydraulically actuated means for picking up a work piece and placing same on the work support, hydraulically actuated means for removing the work from the support at the conclusion of the tooling operation, a single source of hydraulic pressure for operating said hydraulically controlled means, a single valve distributing the pressure to the several hydraulic means, and means for automatically shifting the valve for changing the distribution of the pressure.
22. In a machine tool organization the combination of a tool, a work support for supporting a work piece adjacent the tool, hydraulically actuated means for picking up a work piece and placing same on the work support, hydraulically actuated means for removing the work from the support at the conclusion of the tooling operation, a single source of hydraulic pressure for operating said hydraulically controlled means, a single valve distributing the pressure to the several hydraulic means, and means for automatically shifting the valve for changing the distribution of the pressure including a cam, and a pivoted lever associated with the cam having a connection with the valve.
23. In a machine tool organization the combination of a tool, means for supporting a work piece adjacent the tool, and hydraulically actuated means for picking up a work piece, positioning same on the supporting means, releasing it, and ejecting same from the supporting means at the conclusion of the tooling operation and including a valve having a position for each function of the hydraulic means, and automatically operated means for positioning the valve to cyclically actuate the hydraulically controlled mechanism.
24. In a machine tool organization the combination of a tool, means for supporting a work piece adjacent the tool, and hydraulically actuated means for picking up a work piece, positioning same on the supporting means, releasing it, and ejecting same from the supporting means at the conclusion of the tooling operation and including a valve having a position for each function of the hydraulic means, and automatically operated means for positioning the valve to cyclically actuate the hydraulically controlled mechanism including a rotatable cam, and a pivoted lever having an operative connection with the cam and valve.
25. In a machine tool organization the combination of a tool, means for supporting a work piece adjacent the tool, and hydraulically actuated means for picking up a work piece, positioning same on the supporting means, releasing it, and ejecting same from the supporting means at the conclusion of the tooling operation and including a valve having a position for each function of the hydraulic means, and automatically operated means for positioning the valve to cyclically actuate the hydraulically controlled mechanism including a rotatable cam, a pivoted lever having an operative connection with the cam and valve, and a magazine for supplying work pieces to the hydraulic pick up mechanism.
26. In a machine tool organization the combination of a tool, means for supporting a work piece adjacent the tool, and hydraulically actuated means for picking up a work piece, positioning same on the supporting means, releasing it, and ejecting same from the supporting means at the conclusion of the tooling operation and including a valve having a position for each function of the hydraulic means, and automatically operated means for positioning the valve to cyclically actuate the hydraulically controlled mechanism including a rotatable cam, a pivoted lever having an operative connection with the cam and valve, a magazine for supplying work pieces to the hydraulic pick up mechanism, means for effecting a relative feed between the tool and work while supported, and means synchronizing the feed of the tool and the cyclic operation of the work positioning and ejecting mechanism.

CLEMENT BOOTH.
